Primary Examiner — Dominic Simone(74) *Attorney, Agent, or Firm* — Thomas + Horstemeyer, LLP(57) **CLAIM**

The ornamental design for a shoe, as shown and described.

DESCRIPTION

FIG. 1 is a perspective view of my new design;
FIG. 2 is a front elevational view thereof;
FIG. 3 is a rear elevational view thereof opposite that of FIG. 2;
FIG. 4 is a side elevational view thereof;
FIG. 5 is a side elevational view thereof, from a side opposite that of FIG. 4;
FIG. 6 is a top view thereof; and,
FIG. 7 is a bottom view thereof.
The broken lines shown on the shoe represent thread stitching.
